assignors to B. H. Hubbert & Son, Inc., a corporation
of Maryland

Filed Jan. 8, 1964, Ser. No. 78,123

Term of patent 14 years

(Cl. D81—10)

FIG. 1

FIG. 2

FIG. 3

FIGURE 1 is a side elevational view of a wall-mounted steam kettle, embodying our new design, but presenting the support with the access panel removed therefrom;

FIGURE 2 is a side elevational view, taken from the opposite side of FIGURE 1, and presenting the wall-mounted steam kettle with the access panel of the support in normal position; and

FIGURE 3 is a side elevational view of a modified embodiment of a wall-mounted steam kettle shown in FIGURE 1.

The opposite side of the vessel shown in FIGURE 3 appears the same as the side shown.

The undisclosed top portion of the embodiment shown in FIGURES 1 and 2 is open as indicated by the embodiment shown in FIGURE 3.

We claim:

The ornamental design for a wall-mounted steam kettle, as shown and described.
